UNITED STATES PATENT OFFICE.

JESSE A. WRIGHT, OF SEAFORD, DELAWARE.

SIGNALING DEVICE.

1,270,355.

Specification of Letters Patent. Patented June 25, 1918.

Application filed May 9, 1916. Serial No. 96,388.

To all whom it may concern:

Be it known that I, JESSE A. WRIGHT, a citizen of the United States, residing at Seaford, in the county of Sussex and State of Delaware, have invented new and useful Improvements in Signaling Devices, of which the following is a specification.

This invention relates to fog horn signals, and has particular reference to the 10 mechanism employed for rotating the horn to facilitate signaling.

The invention aims to provide a means whereby the horn preferably mounted upon the pilot house can be rotated from within 15 the latter, and locked in any of its adjusted positions.

The nature and advantages of the invention will be readily apparent when the following description is read in connection 20 with the accompanying drawings, the invention residing in the construction and arrangement of parts as claimed.

In the drawings forming part of this specification like numerals of reference indicate similar parts in the several views and wherein:

Figure 1 is a side elevation.

Fig. 2 is a vertical sectional view.

Fig. 3 is a horizontal sectional view taken 30 on line 3—3 of Fig. 2 looking in the direction of the arrow.

Fig. 4 is a detail view of the base.

Referring more particularly to the drawings in detail 10 indicates the pilot house 35 upon the roof 11 of which is secured the legs 12 which latter supports a base plate 13. Mounted upon the base 13 is a turn table 14 from which rises the standard 15 for supporting the signal horn 16.

Secured to the roof 11 are plates 17 having alined hollow bosses 18 in which is journaled a vertically disposed hollow shaft 19, which latter is also journaled in a sleeve 20 depending from the base 13, through which the shaft

45 extends and is connected with the turn table 14. The opposite end of the shaft projects an appreciable distance within the pilot house, and has associated therewith a handle 21 by means of which the shaft can 50 be rotated in opposite directions, whereupon the turn table 14 is operated to move the horn 16 into any predetermined position. Leading from any suitable source are current wires 22 which latter extend up 55 through the hollow shaft 19 and are connected to the motor 23 of the signal.

Mounted for sliding adjustment within the hollow shaft 19 is a rod 24 having its upper end disposed above the turn table and connected in any suitable manner with the 60 adjacent end of a lever 25 horizontally disposed and pivoted midway at a point between its ends upon the standard 15, while associated with the opposite end of said lever is a locking pin 26 depending therefrom and adapted to be received within alined openings in the base 13 and turn table 14 respectively to hold these parts fixed relatively. The opposite end of the rod 24 extends an appreciable distance below the adjacent end of the hollow shaft 19 65 and is provided with a suitable hand grip 27, by means of which the rod 24 can be adjusted vertically. When the rod is lowered, the lever 25 is rocked upon its pivot in a direction to elevate the pin 26 moving the latter out of engagement with the base 13. In this position of parts, the turn table can be rotated through the instrumentality of the shaft 19 and handle 21, whereby the horn 70 can be arranged in any desired position. The base plate 13 is provided with a plurality of openings 28 for the reception of the locking pin 26, when the opening in the turn table is brought into registry with the 75 particular opening in the base 13, by reason of which construction and arrangement it is manifest that the signal can be held in any of its adjusted positions. Secured to the lever 25 is one terminal of a retractile spring 80 30, the opposite end of the spring being connected to the support 15, the spring operating to normally maintain the locking pin in active position. Obviously this pin 85 is released from its engagement with the 90 base 13 against the action of the spring 30, which latter automatically lowers the pin into engagement with the desired opening 95 in the base upon release of the bar 24.

It is believed that from the foregoing 100 description the advantages of the invention will be readily apparent, however I desire to have it understood that what is herein shown is merely illustrative of one embodiment of the invention, to which I do not 105 limit myself, and that such changes in the construction and arrangement of parts may be resorted to when desired as fall within the scope of what is claimed.

What is claimed is:

1. In a device of the class described, a base, a turn table mounted thereon, a hol-

low shaft journaled in said base and connected with the table to rotate the latter, means for operating the shaft, the lever mounted for locking movement, a locking pin carried by one end of the lever, a spring operating to normally hold the pin in engagement with said table and base to hold these parts fixed relatively, and a vertically adjustable rod arranged within said hollow shaft and having one end connected with the opposite end of the lever to effect a release of said pin.

2. In a device of the class described, a plurality of standards rising from the roof of the pilot house, a base supported upon the upper ends of the standards, a turn table mounted on the base, a hollow shaft

depending from the base and terminating within the pilot house, means connected with the shaft for rotating the latter, a lever mounted for rocking movement, a locking pin depending from one end of the lever for engagement with the table and base to hold these parts fixed relatively, resilient means operating to normally hold the pin in engagement with said parts, a vertically adjustable rod arranged within the hollow shaft and projecting beyond both ends of the latter, said rod being connected with said lever to control the movements of the latter to effect a release of the table.

20 25 30
In testimony whereof I affix my signature.

JESSE A. WRIGHT.
